GLENN H. CURTISS, DECEASED, LATE OF COUNTRY CLUB ESTATES, FLORIDA, BY LENA P. CURTISS, EXECUTRIX, OF MIAMI SPRINGS, FLORIDA

DESIGN FOR A TRAILER VEHICLE

Application filed January 8, 1931. Serial No. 38,236. Term of patent 14 years.

To all whom it may concern:

Be it known that GLENN H. CURTISS, deceased, late a citizen of the United States, residing at Country Club Estates, in the county of Dade and State of Florida, did invent a new, original, and ornamental Design for Trailer Vehicles, of which the following is a specification, reference being had to the accompanying drawings, forming a part thereof, and in which:

Fig. 1 is a plan view of the trailer vehicle, and

Fig. 2 is a side elevation thereof.

The present design comprises as its principal and dominating features the relatively long, low-hung car-like body with bulging roof, the forward portion of said body being tapered to a V-shaped prow, the roof converging downwardly and laterally at its front end to merge with said V-shaped prow, and the underside of said V-shaped prow formed with an upsweep concave curve.

What is claimed is:

The ornamental design for a trailer vehicle, substantially as shown and described.

LENA P. CURTISS,
Executrix for the Estate of Glenn H. Curtiss, Deceased.
